COLD WEATHER INSULATION GARMENT
AND FABRIC

Walter L. Brown, Lansdowne, Pa.

Application May 31, 1951, Serial No. 229,243

10 Claims. (Cl. 2—97)

(Granted under Title 35, U. S. Code (1952),
sec. 266)

1

The invention described herein, if patented, may be manufactured and used by or for the Government for governmental purposes, without the payment to me of any royalty thereon.

This invention relates to cold weather insulation garments and cold weather insulation fabrics.

It is recognized that the effectiveness of a cold weather insulation fabric and a garment made therefrom is caused by dead air space. Felt, wool, cloth and similar bodies are characterized by structure which provides dead air space within itself and, in the case of a garment liner, further provides dead air space bounded by the outer clothing and by the body or inner clothing. However, to be effective as in severe cold, such conventional lining fabrics must either be made of such thickness, or used in a substantial number of superimposed layers, as to constitute a source of discomfort and hindrance to the wearer due to their weight and bulkiness.

An approach taken by the Armed Forces during World War II to the solution of cold weather clothing problem was the adoption of liners of pile fabric, of wool material, having long cut pile threads. Garments equipped with such liners have good thermal insulation properties, but the pile has a tendency to mat, especially after being washed, which greatly lessens its effectiveness.

The present invention overcomes these and other shortcomings heretofore faced by the art, through the provision of a cold weather insulation fabric, and of garments and other articles made therefrom, and essentially consisting of flexible textile warp and filling backing, which carries resilient uncut face loop warps and resilient uncut back loop warps interwoven therewith, the face loop warps and back loop warps being of substantial stiffness and not spontaneously collapsible.

Thus, it is a principal object of my invention to provide a lightweight and durable cold weather insulation garment, which provides a high degree of thermal insulation through dead air pockets.

A further object of my invention is an insulation fabric for manufacturing cold weather garments and other structures.

A still further object of my invention is a cold weather insulation fabric made of industrial tex-

2

tile materials, and which may be manufactured on commercial conventional looms.

A more specific object of my invention is a cold weather insulation fabric (and garments made therefrom) having a fairly loosely woven cotton backing, and uncut erect rows of face loops and back loops of resilient textile material such as mohair yarn, worsted type wool yarn, or a mixture of mohair and wool yarn.

19 The foregoing and other objects of my invention will more fully appear from the following description and illustration of several embodiments of my invention.

In the drawings,

15 Figure 1 is a perspective view, partly broken away, of a cold weather jacket, equipped with an insulation layer, in accordance with my invention;

Figure 2 is a perspective view of a vest-like item of cold weather insulation clothing, which may be worn as a liner or as a separate layer;

20 Figure 3 is a perspective view of a cold weather insulation fabric in accordance with my invention;

Figure 4 is a schematic sectional view, taken along lines 4—4 on Fig. 3;

25 Figure 5 is an example of a weaving plan of a cold weather insulation fabric as shown in Figs. 3 and 4;

Figures 6 and 7 are alternate weaving plans for cold weather insulation fabrics in accordance with the present invention;

Figure 8 is a schematic edge view of a two-layer cold weather insulation fabric, having a wind resistant outer fabric layer and an insulation lining; and

30 Figure 9 is a schematic view of a three-layer cold weather insulation fabric, having a wind resistant outer fabric layer, insulation lining, and a bottom fabric layer.

More particularly, in Figure 1 of the drawings, reference numeral 10 denotes an outer garment in jacket form, which is preferably of wind resistant and water repellent cotton, wool, or other textile material. The cold weather insulation fabric in accordance with the present invention (which will be described in greater detail below) forms an intermediate layer at 11, which may be stitched to the outer layer 10, or buttoned, snap-fastened, slide-fastened, or otherwise connected

thereto in a manner well known to the art; the lining fabric may also extend into the sleeves, as shown at 11'. A lower layer 12 of conventional textile material and weave construction, e. g. of cotton or rayon confines the intermediate insulation layer 11. The multiplicity of dead air pockets formed by the stiff loops of insulation fabric 11 between top layer 10 and bottom layer 12 provide a high degree of thermal insulation, without impairing the flexibility of the garment. Bottom layer 12 may be omitted; in such a case, the shirt of the wearer serves as the lower boundary for the dead air pockets. It will be understood, of course, that trousers, gloves, one-piece suits, and other garments may be constructed in the same general manner as the jacket illustrated in Fig. 1.

Instead of a multi-layer garment, as shown in Fig. 1, an item of cold weather insulation underclothing can be made separately, such as the vest-like garment shown in Fig. 2. This undergarment consists substantially in its entirety of the cold weather insulation fabric 11", about to be described in detail, with resilient loops extending inwardly and outwardly. In use, an undergarment is placed over the shirt and under the outer jacket, and provides dead air space insulation in accordance with the principle above set forth.

A typical cold weather insulation fabric in accordance with the present invention is shown in Fig. 3. A flexible textile backing 13 may consist of cotton. Uncut resilient pile loops 14 are arranged in rows on the face of the backing, and uncut resilient pile loops 15 are arranged in similar rows at the back of the backing. The uncut pile loops of front and back are made of textile material having greater stiffness than cotton, e. g. of mohair spun wool yarn (e. g. worsted), or a blend of mohair and wool (e. g. 50:50). Synthetic mono- or multi-filaments may be substituted for the mohair and/or wool, as for instance crimp-set nylon, described in U. S. Patent No. 2,157,117, Miles. It will thus be understood that the selection of a suitable material for the uncut pile loops may be made from a variety of textile materials, as long as the resulting loops have the desired resiliency and capacity of staying erect, so as to form the desired dead air pockets. Similarly, other flexible textile materials, may be substituted for the cotton material of textile backing 13; however, I prefer cotton for its relative cheapness and strength.

The following data for a typical cold weather insulation fabric in accordance with the present invention are given by way of example, with the clear understanding that such data are merely by way of illustration and are not intended in any way to limit the scope of the invention:

Weight of cloth: 16 oz. per square yard.

Ground warp: 36 threads per inch, two-ply cotton yarn.

Ground filling: 60 threads per inch, two-ply cotton yarn.

Pile warp (face): 9 threads per inch; two-ply yarn mohair, wool, or synthetic material.

Pile warp (back): 9 threads per inch; two-ply yarn mohair, wool, or synthetic material.

Face loops: 135 loops per square inch; loop height $\frac{3}{16}$ ".

Back loops: 135 loops per square inch; loop $\frac{3}{16}$ ".

It is, of course, essential that the face and back loop threads be firmly anchored to the textile backing. A W pile weave, a construction

well known to makers of pile fabrics, is well suited to accomplish this. In a typical W pile weave, the loops are interwoven with the ground, each pile loop being, for instance, under one, over two, and under one pick in a W weave construction. As shown in Fig. 3, the rows of face loops and back loops alternate; however, the pile warp ends may be interwoven with the textile backing in such a manner that the same pile warp alternately extends above and below the backing fabric, thereby forming a series of uncut loops above and below the backing.

The diagrammatic showing of Fig. 4 illustrates, in greatly exaggerated form, the way in which the face and back pile loops are interwoven with the textile backing, so as to afford a fabric construction in accordance with the principle of the present invention. Cotton ground warp threads 16 and 17 and cotton ground filling threads 18, form a plain weave, constituting the textile backing. Mohair (or other resilient animal or synthetic) pile warp thread 19 is interwoven with ground filling threads 18, so as to form a face loop extending upwardly from the textile backing between every four ground filling threads. Similarly, pile warp thread 20, which is of the same material as 19, is interwoven with ground filling threads 18, so as to form a back loop extending downwardly from the textile backing between every four ground filling threads, and in staggered relation to the face loops formed by pile warp thread 19. Ground warp face pile warp thread 19 and back pile warp thread 20 are spaced from each other by the ground warp threads. Temporary pile threads 21, 22 (shown in dotted lines), which are inserted in the loom for the formation of the face and back pile loops in a manner well known to the art, are withdrawn in the course of the manufacture of the fabric. The configuration of the pile loops which in the idealized showing of Fig. 4 resembles a U, is in actual fact spiraled due to the resiliency of the loop-forming textile material, with the legs of the loops forming an angle, as shown in Fig. 3. Similarly, the spacings between back filling threads 18 are not drawn to scale in Fig. 4, but vary in accordance with the internal stress exerted by the resilient material of the loops.

The weaving plan of Fig. 5 constitutes a typical example of an insulation pile fabric woven on a loom without the use of wires. Vertical row 1-6 denotes the filling picks; picks 1 and 4 being temporary threads which are removed off the loom. Horizontal row 1-8 denotes the warp ends, which are further designated G for the ground ends, FP for the face pile end, and BP for the back pile end.

The alternate weaving plan of Fig. 6 is likewise adapted for looms other than wire looms. Picks 1 and 2 are temporary, and are removed from the cloth off the loom to form the pile threads.

The weaving plan of Fig. 7 is adapted for wire looms. A full repeat of the weave includes four ground ends and two pile ends in the warp, and four picks in the filling. The insertion and withdrawal of the pile wires is a manipulation well known to the pile fabric trade and needs no further illustration or description.

While a principal use of insulation fabric, in accordance with the present invention, is in the manufacture of cold weather garments, it may also be put to other uses in the art of insulation, e. g. as a tent liner for a tent having an outer and inner ply of canvas, or nylon, or simi-

lar material. The dead air space formed by the upstanding loops of the insulation fabric 11 between the top layer 10' and bottom layer 12' (see Fig. 9) serves as a highly efficient insulation medium. The liner may also be constructed from a layer of insulation fabric 11 and a layer of conventional wind resistant fabric 23, in the two-ply construction diagrammatically illustrated in Fig. 8. Such a liner can be attached to the inside or outside of a tent or other shelter, insulation fabric 11 occupying an intermediate position for the provision of dead air space thermal insulation.

For camouflage in items of military use, and for decorative effect in other items, the pile threads 19 which constitute the face loops may be of one color, e. g. white, and the pile threads 20 which constitute the back loops, may be of another color, e. g. olive drab. Other color combinations may, of course, be substituted, if desired.

An insulation fabric made in accordance with the foregoing principles is characterized by a loop structure of relatively stiff, compression-resistant and highly resilient textile yarns (or mono-filaments) supported by a lightweight backing fabric intermediate the face and back loops which serves to retain the loops in a structural system which is pliable in two dimensions but resistant to compression in the third (thickness) dimension; the arched configuration of the loops enhances the compression resistance of the loops. A garment in which the insulation fabric is incorporated is drapable and washable.

It is evident that departures and variations in details may be made without departing from the spirit of the invention. I therefore desire to encompass such variations within the scope of my invention, as defined by the appended claims.

I claim:

1. A cold weather jacket comprising an outer fabric layer of jacket configuration and an insulation liner comprising a flexible textile backing and pile warps interwoven with said backing, said pile warps being of resilient textile material of substantially greater stiffness than said backing and forming erect individual face loops and back loops highly resistant to compression, each of said individual face loops being spaced from any of the other face loops immediately above the surface of said backing and each of said individual back loops being spaced from any of the other back loops immediately below the surface of said backing, whereby a plurality of insulating dead air pockets is formed beneath said outer fabric layer.

2. A cold weather garment comprising an outer fabric layer conforming to the shape of a body or body member and an insulation liner comprising a flexible textile backing and pile warps interwoven with said backing, said pile warps being of resilient textile material of substantially greater stiffness than said backing and forming erect individual face loops and back loops highly resistant to compression, each of said individual face loops being spaced from any of the other face loops immediately above the surface of said backing and each of said individual back loops being spaced from any of the other back loops immediately below the surface of said backing, whereby a plurality of insulating dead air pockets is formed beneath said outer fabric layer.

3. Cold weather insulation underclothing comprising a flexible textile backing of the config-

uration of a human body or body portion, and pile warps interwoven with said backing, said pile warps being of resilient textile material of substantially greater stiffness than said backing and forming erect individual face loops and back loops highly resistant to compression, each of said individual face loops being spaced from any of the other face loops immediately above the surface of said backing and each of said individual back loops being spaced from any of the other back loops immediately below the surface of said backing, whereby a plurality of insulating dead air pockets is formed beneath the outer clothing.

4. A cold weather insulating lining fabric comprising a flexible textile backing and pile warps interwoven with said backing, said pile warps being of resilient textile material of substantially greater stiffness than said backing and forming erect individual face loops and back loops highly resistant to compression, each of said individual face loops being spaced from any of the other face loops immediately above the surface of said backing and each of said individual back loops being spaced from any of the other back loops immediately below the surface of said backing, whereby a plurality of insulating dead air pockets is formed when said lining fabric is placed beneath an outer fabric layer.

5. A fabric according to claim 4, wherein said textile backing is cotton and wherein said pile warps are mohair.

6. A fabric according to claim 4, wherein said textile backing is cotton and wherein said pile warps are spun wool yarn.

7. A cold weather insulation lining fabric comprising a flexible textile backing and erect individual face loop warps and back loop warps interwoven with said backing, said face and back loop warps being of resilient textile material of substantially greater stiffness than said backing and being highly resistant to compression, each of the face loops formed by said face loop warps being spaced from any of the other face loops immediately above the surface of said backing and each of the back loops formed by said back loop warps being spaced from any of the other back loops immediately below the surface of said backing, whereby a plurality of insulating dead air pockets is formed when said lining fabric is placed beneath an outer fabric layer.

8. A fabric according to claim 7, wherein said back loop warps are of a color contrasting with the color of the face loop warps.

9. A cold weather fabric comprising an outer fabric layer and an insulation layer comprising a flexible textile backing and pile warps interwoven with said backing, said pile warps being of resilient textile material of substantially greater stiffness than said backing and forming erect individual face loops and back loops highly resistant to compression, each of said individual face loops being spaced from any of the other face loops immediately above the surface of said backing and each of said individual back loops being spaced from any of the other back loops immediately below the surface of said backing, whereby a plurality of insulating dead air pockets is formed beneath said outer fabric layer.

10. A cold weather fabric comprising a top fabric layer, a bottom fabric layer and an insulation layer comprising a flexible textile backing and pile warps interwoven with said backing, said pile warps being of resilient textile material of substantially greater stiffness than said backing

7
and forming erect individual face loops and back loops highly resistant to compression, each of said individual face loops being spaced from any of the other face loops immediately above the surface of said backing and each of said individual back loops being spaced from any of the other back loops immediately below the surface of said backing, whereby a plurality of insulating dead air pockets is formed between said top layer and bottom layer.

10 WALTER L. BROWN.
